UNITED STATES PATENT OFFICE

2,079,040

FASTENING INSERTING MACHINE

Charles A. Robinson, Salem, Mass., assignor to
 United Shoe Machinery Corporation, Paterson,
 N. J., a corporation of New Jersey

Application February 12, 1936, Serial No. 63,613

14 Claims. (Cl. 1—11)

The present invention relates to fastening inserting machines, for example staple forming and driving machines. The illustrated machine embodying the invention is especially designed for sealing radio tube cartons.

A typical staple forming and driving machine is that shown in United States Letters Patent No. 1,016,930, granted February 13, 1912, upon an application of William H. Borden. Such a machine is provided with a wire feeding mechanism, an inside former over which the wire is fed, a cutter for then severing an unformed staple from the main body of the wire, an outside former for bending the staple legs over the inside former, a driving throat, means for retracting the inside former from the driving path, and means for driving the staple through the work against an anvil. In such machines, as found in use, the anvil is movable downwardly to admit the work and to permit its movement through the machine, and is moved upwardly to hold the work firmly against the throat prior to the driving of a staple. Such machines drive several staples per second and are generally used to fasten substantially flat pieces of work together.

The art is in need of a machine which will be more convenient than the movable anvil machine for use on work of such a nature that its upward movement with the anvil engenders difficulty, or inconvenience. Such work, for example, is the stapling of various types of ornaments to shoes, as bows, straps, pompons, stapling shank pieces to insoles, and the like. Such work requires careful adjustment of the piece to be stapled upon the main work piece, together with the preservation of the adjustment until after the staple is driven. To this end, it is desirable that the work, once arranged, should not run the risk of disturbance by a movement of the anvil.

It has already been proposed to move the staple driving mechanism up and down above a stationary anvil, for the purposes above discussed, and to omit the driving throat, driving the staple directly from the outside former into and through the work. Thus, the lower portion of the outside former, instead of having merely the movement necessary to bend the staple legs, must then have a range of movement extending from the anvil to the upper surface of the inside former, which is much greater than the convenient handling of such work requires, involves some mechanical difficulty in a rapidly operating machine, and engenders the serious practical difficulty that when the outside former is remote from the anvil it is so far from it (two inches or more) that the op-

erator has difficulty in placing his work accurately under the outside former upon the anvil, which is hidden by the work, and the staples are therefore not driven with sufficient accuracy. It has not been practicable to lower the inside former sufficiently to avoid this disadvantage without risking interference between the operator's hands or the work and the wire feeding mechanism, which is located at the level of the top of the inside former.

It is an object of the present invention to provide a simple, cheap and convenient machine for the purpose discussed, which will avoid the disadvantages mentioned. I have accordingly provided a machine in which the throat is retained and is movable instead of the anvil, to the extent, only, that is requisite to accommodate the types of work discussed (roughly $\frac{3}{4}$ inch), thus avoiding undue movement of the outside former. I have found it advantageous also to reduce to a minimum the amount of metal so moved. Accordingly, the reciprocating parts (aside from the driver) have been limited to the throat, the outside former and the wire cutter, and to avoid complicating the machine with separate operating means for them all, I have mounted them all on one slide, so that they all have the same movement and a single operating means suffices for all. While a movement as great as $\frac{3}{4}$ of an inch is not necessary for the outside former and cutter, it does not prejudice the successful operation of the machine.

It is necessary, in staple forming machines, to provide a space below the outside former, and beside the inside former, in which the legs of a staple being formed may have room to swing, and it is also necessary, in machines driving staples formed of fine wire, to provide a guide which will support them against crippling, while being driven. In other words, there must be a continuous guide from the lower end of the outside former to the lower end of the throat. These requirements are all met by the present invention, in accordance with which the outside former and throat are fixedly mounted in separated positions upon the slide above mentioned, and a movable guide wall carrying block is mounted in the interval between them. This block is movable outward to provide the requisite space for inserting the unformed staple and bending the staple legs and movable inward to close the opening and complete the guide passage after the formation of the staple.

This structure enables the machine to be used upon work requiring a considerable opening be-

tween the anvil and throat for arranging the work, without making the opening disadvantageously large and without danger of disturbing the arrangement of the work by movement of 5 the anvil, while the small mass of the reciprocating parts does not engender undue vibration when run at the speed usual for such machines.

The illustrated machine is designed for the express purpose of sealing radio tube cartons. 10 The ordinary such carton consists of a straight prismatic pasteboard tube with flanged end caps inserted in its ends and it is desired to staple the flanges of the caps to all of the sides of the tube. Such a machine, to be convenient in use, 15 should be arranged to drive one staple in each side of the tube and then stop, to permit changing the work or changing ends on the same piece. It is desirable also to provide an automatic work handling mechanism which will turn the carton 20 to the proper position to receive each staple.

It is a further object of the present invention to satisfy these requirements. I have accordingly provided a mechanism for holding and centering the work piece, for rotating it an aliquot 25 part of 360° in each staple forming and driving cycle, and for stopping it after the work piece has been rotated 360° . Thus, all skill on the part of the operator in managing the work so as to center the staples properly and in stopping 30 the machine promptly is rendered unnecessary.

In accordance with further features of the invention, the machine is capable of driving one staple, if desired, and then stopping automatically, and the work holder is adjustable to a broad range of sizes of cartons without loss of 35 rapidity and accuracy.

These and other features of the invention comprising certain combinations and arrangements of parts will be apparent from the following description of a preferred embodiment of the invention shown in the drawings, in which—

Fig. 1 is a front elevation of the staple forming and driving mechanism;

Fig. 2 is a side elevation, partly in section, 45 of the staple forming and driving mechanism;

Fig. 3 is an enlarged detail of the same;

Fig. 4 is a section on the line IV—IV of Fig. 3;

Fig. 5 is a perspective detail of the same;

Fig. 6 is a section on the line VI—VI of Fig. 2;

Fig. 7 is a side elevation of the whole machine;

Fig. 8 is a detail, partly in section, of the work handling mechanism;

Fig. 9 is a perspective view of a work piece; and

Figs. 10 and 11 are enlarged perspective details of the work handling mechanism.

The machine is operated from a main shaft 10 mounted in the upper part of the main frame 12. The front end of the shaft 10 carries a radially 60 adjustable arm 14 having a roll 16 at its outer end. The roll, as it swings around the axis of the shaft, depresses a lever 18 pivoted at 20 on the main frame. The lever 18 is connected to a driver plunger 22 by a short link 24. The plunger 22 slides vertically in a guideway formed in a second plunger 26, which is itself mounted in a guideway in the main frame, and is moved vertically by a lever 28 also pivoted at 20 and having a roll 30, running in a cam slot 32, in a disk 34 mounted 65 on the shaft 10. The driving end of the lever 28 has a slot 35 working on a roll 36 on the upper end of the plunger 26. The lever 18 is raised by a spring 38, and the lever 28 is operated in both 70 directions by its cam 32.

75 The inside former 40 is mounted to slide for-

ward and backward horizontally in a guideway in the main frame 12. It has no vertical movement. It is spring pressed toward operative position by a spring 42, in which position shoulders 43 (Figs. 2 and 5) abut against a surface on the slide or plunger 26 and the former 40 is forced back into inoperative position by a cam lug 44 pivoted on the frame 12, and operated by the plunger 26 as it descends. This withdrawal occurs after the outside former has descended and formed the staple, as is common in machines of this type.

The outside former 46 and driving throat 48 are fixedly mounted on the plunger 26. The driver 50 is mounted on the plunger 22, and works in a guideway 52 formed in the body of the outside former 46. This guideway is normally continuous with guideways 54, 56 formed above and in the driving throat 48. The legs of the staple slide down the guideways 52, 54, 56 as the staple is being driven, and the guideways 52, 54, 56 permit free passage of the driver 50.

The guideway 54 is formed in a little block 58, mounted in a slot 59 in the front of the throat 48, and capable of forward and backward sliding movement in the slot relatively to the plunger 26. It has a dowel 60 projecting from its rear face which slides in a hole in the throat 48, and is normally pulled back into such a position that the guideways 52, 54, 56 are all in line, by a spring 62.

It is forced outward and forward by a cam surface 64 (Fig. 7) on the main frame, cooperating with the rear end of the dowel 60 as the plunger 26 descends. This displacement is for the purpose of permitting the legs of the staple being formed to be bent down behind it, in the space 65, in position to fit in the guideway 54 when the block 58 returns to normal position, after the staple has been formed, the dowel 60 having then passed the cam 64.

The staple forming and driving parts are covered by a slotted cover plate 202 (Fig. 1) which permits easy inspection. The block 58 is readily removable, by disconnecting the spring 62, and permits easy relief of clogging or other trouble 45 below the driver 50.

The wire handling mechanism is shown best in Fig. 1. The wire 80 is drawn from a reel (not shown) and passes into a guide 82 between two feed wheels 84, 86. The wheel 86 is an idler and is mounted on a lever 88 pivoted at 90 and spring held toward the wheel 84. A lug 92, on the lever 28, forces the lever 88 counterclockwise as the lever 28 swings down, to release the wire 80 at such time, in order that the resetting of the 55 wheel 84 may not withdraw the wire. The wire 80 passes through a conduit 94 at the end of which is an adjustable hardened die 96 the exit orifice in which serves as a cutter. A movable cutter 98, adjustably bolted at 99 to the plunger 26, cooperates with the die 96 to sever a piece of wire as the plunger 26 descends. The wheel 84 is oscillated by an arm 100 mounted on the axis of the wheel 84, and operated by a link 102 adjustable in a slot in the arm 100, and connected to an eccentric strap 104 on the shaft 10.

The machine is so timed that the wheel 86 is separated from the wheel 84 when the arm 100 is swinging clockwise, so that the wire 80 will never be dragged backward by the reverse movement of the feed wheel 84. The length of the severed piece of wire, and hence the length of the legs of the staple to be formed, is regulated by adjusting the die 96, and the adjustments of 70 75 80 85 90 95 100 105 110 115 120 the cutter 98 and of the link 102 in the slot in the arm 100.

As above stated, the illustrated machine is designed for the specific purpose of stapling radio tube cartons. Such cartons consist of square hollow tubes 110 (Fig. 9) with inserted caps 112 at the ends. The caps 112 have flanges 114 which nest inside the ends of the tubes 110; and are fastened in place by staples 116, which it is the purpose of the illustrated machine to form and drive. The tube 110 is held between four slightly resilient arms 118 (Figs. 7, 8 and 10), so as to hold a flange 114 over and in contact with an anvil 120 directly beneath the throat 48.

15 The arms 118 are supported on a rotating head 122 in which they are radially slideable. Each arm 118 has a pin 124 working in a cam slot 126 in a swivel plate 128 held in adjusted position by a screw 129 which also acts as one of the pins 124. Turning the swivel plate 128 adjusts the arms 118 simultaneously to fit any size of tube 110 and to center it on the axis of the swivel plate. The head 122 is mounted on a hollow shaft 130 working in a bearing 132, which is vertically adjustable at 134 to compensate for varying thicknesses and sizes of work, the anvil 120 being rigidly mounted on the frame 12 by means of the shaft 136 which extends through the hollow shaft 130.

30 It is necessary to adjust the work carrier vertically when the arms 118 are spread wider apart in order to make the work rest on the top of the anvil 120 properly, and also in order that the arms 118 may not strike the throat 48 when 35 they are rotated. A safety device is provided to insure that this be done. When the lower right-hand arm 118 (Fig. 10) is moved outward far enough, it strikes one arm of a little bell crank 137 mounted on the bearing slide 132a and having a cam slot 137a in its other arm cooperating with a pin 137b on a frame member 186 (Fig. 10). Thus, the arms 118 cannot be moved out far enough to interfere with the throat without interference with the member 137, which will remind the operator that he must vertically drop the 40 whole work carrier. The element 130 is driven by an Oldham coupling 138 connecting it with a rotatable member 140 on the shaft 136. The member 140 has four teeth shown as pins 142 45 equally spaced around its periphery. These pins are successively engaged by a hook 144 on a rod 146 operated by an eccentric strap 148 (Fig. 7) on the shaft 10, rotating the work carrier 90° at each revolution of the shaft 10. Overthrowing of the work carrier is prevented by a spring pawl 150 (Fig. 11) which engages successively in appropriate notches 151 in the member 140.

50 The illustrated machine is constructed to drive four staples at each actuation and then to stop to enable the operator to insert a new carton end for stapling. This is accomplished as follows, referring particularly to Fig. 7. The treadle rod 152 tips a bell crank 154, pivoted at 156, clockwise. This bell crank has a vertical arm 158, which is thrown out from under the disconnecting cam 160 of a Horton clutch, thus permitting the continuously driven pulley 162 to engage and drive the shaft 10. Another vertical arm 164 of the bell crank 154 pulls to the right (Fig. 7) a rod 166 having a roll 168 on its front end. When the machine is at rest the roll rests in a depression 170 (Fig. 11) in the periphery of the member 140. After the member 140 has turned slightly the roll 168 rides on its periphery and holds the bell crank 154 in tripped position, until the de-

5 pression 170 comes around again and releases the rod 166 and bell crank 154. The bell crank is then thrown counterclockwise by the spring 172, and the member 158 catches the cam 160 as soon as it comes around, and stops the machine, the operator having released the treadle after the first staple has been driven. The stopping of the machine is facilitated by a brake disk 174 which slides to the right along the shaft 10 (Fig. 7) against a disk 175 fast on the shaft 10. This disk 175 is released, when the machine is treadled, by the link 176, connecting the arm 164 and a toggle 178, which, when broken by treadling the machine, pulls the lever 180 counterclockwise. The lever 180 then forces the yoke 182 counterclockwise, about the fixed pivot 184 of the lever 180, and thus frees the brake disk. When the roll 168 falls into the depression 170, the toggle 178 straightens and the brake is set.

10 The anvil and work supporting shaft 136 (Fig. 20 8) is mounted on a frame bracket 186 which is pivotally mounted on the main frame at 188, and is supported by a strong spring 190 (Fig. 7), so that the anvil has a certain amount of resilience, under the blow of the driving throat 48. A rotary 25 adjustment about the center 188 is provided at 192 and a vertical adjustment between two parts of the bracket 186 is provided at 194, 195 (Figs. 7 and 11).

15 It will sometimes be desired to drive one staple only, stopping the machine at the end of one revolution instead of four, as above described. In such case the operator will throw up a little finger 196 (Fig. 10), to the dotted line position, in which it will cam out the wedge-shaped end 35 of the hook 144 against the spring-pressed lever 198 pivoted at 200 on the member 186, as the hook is lowered, and prevent its engaging a pin 142 as it rises. This prevents the turning of the work carrier, and the roll 168 will drop back into 40 the depression 170 as soon as the treadle is released. Ordinarily the operator will hold the treadle down until after the first staple is driven, so that the turning of the work carrier will keep the machine in operation, but in case only one 45 staple is to be driven the operator will merely tap the treadle.

Having described my invention, what I claim as new and desire to secure by Letters Patent of the United States is:

50 1. In a stapling machine, an inside former, a reciprocable outside former and a reciprocable driving throat having the same amplitude of reciprocation and the same actuating means, the outside former and the throat having aligned guides for a formed staple, and being separated by an interval corresponding to the length of the longest staple the machine is designed to handle, a filler block constructed to fill the said interval and having a staple guide arranged to align with the previously mentioned guides when the block is in operative position, means timed to withdraw the filler block after a staple has been driven to provide a space for the feeding of a succeeding unformed staple over the inside former and for the bending of its legs by the outside former, means for returning it to operative position after the said succeeding staple is formed, means for moving the inside former from the driving path of the formed staple, and a driver for driving the staple through the guides in the filler block and throat, the filler block remaining in operative position during the driving of the staple and being displaced therefrom only by the means described above.

2. In a stapling machine, a normally fixed anvil, a reciprocable slide carrying a driving throat, the throat and the slide above the throat being provided with a guide for the driving of a formed staple therein, a side wall of the guide above the throat being removable away from the opposed wall to provide an opening through which an unformed staple may be fed and in which the legs of the said unformed staple may be bent as it is formed, a cam on the machine frame for removing the said side wall, and means for replacing the said removable wall to complete the driving guide, after the formation of the staple.
3. In a stapling machine, a normally fixed anvil, a reciprocable slide carrying a driving throat, the throat and the slide above the throat being provided with a guide for the driving of a formed staple therein, cam means on the main frame of the machine and on the slide for moving a side wall of the guide above the throat away from the opposed wall to provide an opening through which an unformed staple may be fed and in which the legs of the said unformed staple may be bent as it is formed, and means for replacing the said removable wall to complete the driving guide, after the formation of the staple.
4. In a staple forming and driving machine, an anvil, an inside former located at a fixed distance above the anvil, a slide carrying an outside former movable to cooperate with the said inside former to form a staple and a driving throat located at a fixed distance below the outside former, a filler block constructed to bridge the said fixed distance and to be withdrawn while the staple is being formed, to provide a space for feeding an unformed staple over the inside former and for bending its legs, said throat and said filler block, when it is in closed position, forming a continuous guide for the formed staple while it is being driven, a cam located between the machine frame and the filler block for moving the filler block, and a cam located between the slide and the inside former for withdrawing the inside former after the formation of the staple.
5. In a staple forming and driving machine, an anvil, a driver, an inside former located at a fixed distance above the anvil, an outside former movable to cooperate with the said inside former to form a staple, a driving throat located at a fixed distance below the outside former, and a filler block constructed to bridge the said fixed distance and to be withdrawn while the staple is being formed, to provide a space for feeding an unformed staple over the inside former and for bending its legs, said throat and said filler block, when it is in closed position, forming a continuous driver-fitting guide for the formed staple while it is being driven.
6. In a stapling machine, a staple driving means, a work holder arranged to hold a work piece around the periphery of which staples are to be driven, mechanism for giving said work holder a step-by-step rotation, one step in each staple driving cycle of the machine, a clutch controlling member, and a cam mounted integrally with the work holder cooperating with the member to hold the clutch in operation until the work holder has rotated 360° and then to disconnect the clutch.
7. In a stapling machine, a staple driving means, a work holder arranged to hold a work piece around the periphery of which staples are to be driven, mechanism for giving said work holder a step-by-step rotation, one step in each staple driving cycle of the machine, a driving clutch resiliently urged toward inoperative position, a member arranged to hold the clutch in operative position, and a cam mounted integrally with the work holder arranged to cooperate with the said member to hold the clutch in operative position during a complete rotation of the work support, and to release said member at the end of such rotation to stop the machine.
8. In a stapling machine, staple driving mechanism, an anvil, and a work support arranged to hold and to rotate a work piece between the anvil and the staple driving mechanism, said work support having work contacting members simultaneously and equally adjustable toward and from the axis of rotation of the work support to accommodate work of different sizes.
9. In a stapling machine, staple driving mechanism, an anvil, a work support arranged to hold and to rotate a work piece between the anvil and the staple driving mechanism, said work support having a head and a plurality of work holding fingers laterally adjustable to different fixed positions on said head, and a member arranged to effect such adjustments of all the said fingers simultaneously and equally.
10. In a stapling machine, staple driving mechanism, an anvil, and a work support arranged to hold and to rotate a work piece between the anvil and the staple driving mechanism, said work support having work contacting members simultaneously adjustable toward and from the axis of rotation of the work support to accommodate work of different sizes.
11. In a stapling machine, staple driving mechanism, an anvil, a work support arranged to hold and to rotate a work piece between the anvil and the staple driving mechanism, said work support having work contacting members simultaneously adjustable toward and from the axis of rotation of the work support, the work support, as a whole, being adjustable along the line in which the driving mechanism operates, to bring work of varying sizes, when held in the work support, into proper relation to the anvil.
12. In a stapling machine, staple driving mechanism, an anvil, a work support arranged to hold and to rotate a work piece between the anvil and the staple driving mechanism, said work support having work contacting members simultaneously adjustable toward and from the axis of rotation of the work support, the work support, as a whole, being adjustable along the line in which the driving mechanism operates, to bring work of varying sizes, when held in the work support, into proper relation to the anvil, and a member for inhibiting the said adjustment of the work contacting members beyond a certain amplitude, unless the work support, as a whole, is adjusted away from the staple driving mechanism, in order to prevent interference between the work contacting members and the staple driving mechanism.
13. In a stapling machine, staple driving and

5. clenching means, a rotatable work holder, means for giving the work holder a rotation of an aliquot part of 360° in each staple driving cycle of the machine, said means comprising teeth on the holder and a reciprocable pawl engaging said teeth, one by one, to turn the holder, and a member for inhibiting the action of said pawl, in case it is desired to drive only one staple in a work piece.
10. 14. In a stapling machine, staple driving and clenching means, a rotatable work holder, means

for giving the work holder a rotation of an aliquot part of 360° in each staple driving cycle of the machine, said means comprising teeth on the holder and a reciprocable pawl engaging said teeth, one by one, to turn the holder, said pawl having a cam surface, and a cam member movable to engage said cam surface to direct the pawl away from said teeth, to inhibit the rotation of the work holder, when desired.
